214,709

HAIR COMB

John Karfo, 207 E. 74th St., New York, N.Y. 10021,
and Dante P. Ieserek, 2198 Jones Road, Fort Lee,
N.J. 07024

Filed Sept. 29, 1967, Ser. No. 8,789

Term of patent 14 years

Int. Cl. D28—03

U.S. Cl. D86—8

FIG. 1 is a top plan view of a hair comb embodying our new design;

FIG. 2 is a right side elevational view, the left side being a mirror image thereof; and

FIG. 3 is a front perspective view of our hair comb.

We claim:

The ornamental design for a hair comb, as shown and described.

References Cited

UNITED STATES PATENTS

D. 139,381 11/1944 Harris.
D. 184,870 4/1959 Heinrich ----- D86—8

2,642,070 6/1953 Lubin et al. ----- D86—8 X
D. 187,724 4/1960 Freeman ----- D86—8

OTHER REFERENCES

Premium Practice, April 1967, p. 179, Jet-age Sales Corp. advertised hair dryer comb.

EDWIN H. HUNTER, Primary Examiner

LOIS LANIER, Assistant Examiner